Des. 235,730
Patented July 8, 1975

235,730

CARRYING CASE HANDLE

George W. Bush, Haddonfield, N.J., assignor to
P.H.C. Industries, Inc., Camden, N.J.

Filed Jan. 8, 1973, Ser. No. 321,812

Term of patent 14 years

Int. Cl. D8—06

U.S. Cl. D8—154

FIG. 1

FIG. 5

FIG. 2

FIG. 6

FIG. 3

FIG. 7

FIG. 4

FIG. 8

FIG. 1 is a side elevational view of a carrying case handle embodying my new design, the opposite side being a mirror image of the side shown;

FIG. 2 is a top plan view thereof;

FIG. 3 is a bottom plan view thereof;

FIG. 4 is an end elevational view, the opposite end being the same in appearance;

FIG. 5 is a view similar to FIG. 1 showing a modified form of my new design, the opposite side being a mirror image of the side shown;

FIG. 6 is a top plan view thereof;

FIG. 7 is a bottom plan view thereof; and

FIG. 8 is an end elevational view thereof, the opposite end being the same in appearance.

I claim:

The ornamental design for a carrying case handle, as shown and described.
